CLAIM

The ornamental design for a connector for attaching an activated pull cord to an electric switch, as shown and described.

DESCRIPTION

FIG. 1 is a bottom perspective view of a connector for attaching an activating pull cord to an electric switch showing our new design;

FIG. 2 is a top plan view thereof on an enlarged scale; FIG. 3 is a front elevational view thereof on an enlarged scale;

FIG. 4 is a right side elevational view thereof on an enlarged scale, the left side being a mirror image;

FIG. 5 is a rear elevational view thereof on an enlarged scale; and,

FIG. 6 is a bottom plan view thereof on an enlarged scale.
